UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

GARMENT SUPPORTER.

Application filed June 30, 1926. Serial No. 119,520.

My invention relates to an improvement in garment supporters, and has for one of its objects the provision of a supporter embodying a base plate of improved and novel construction.

A still further object of my invention is the provision of a garment supporter in which the button is of improved construction in that the same is an imperforate structure, no rivets or similar fastening devices being employed for attaching the button to its base plate.

A still further object of my invention is the provision of a garment supporter in which the means that secures the button to the base plate is maintained out of engagement with the holding loop of the supporter at all times, thereby reducing wear on the hose due to friction between the holding loop and the means by which the button is held attached to its base plate.

In garment supporters, particularly hose supporters, as now constructed, it is customary to rivet the button to a base plate, the base plate in turn being supported by a non-elastic member or pendant. Inasmuch as these buttons are usually made of rubber, they in time harden and become brittle and frequently tear away from the rivet, thereby rendering the device unfit for further use. As above pointed out the garment supporter of the present invention is so constructed as to eliminate the use of these holding rivets and hence eliminate the danger of tearing or breaking the button away from the base plate.

Inasmuch as my invention may take a number of different forms in actual practice, I have illustrated several embodiments thereof in the accompanying drawings, in which—

Fig. 1 shows one embodiment of my invention in perspective;

Fig. 2 the device of Fig. 1 in part sectional elevation;

Fig. 3 the button of Figs. 1 and 2 in elevation;

Fig. 4 a base plate of the type illustrated in Figs. 1 and 2;

Fig. 5 shows in part sectional elevation a garment supporter structure modified somewhat with respect to the construction illustrated in Fig. 1;

Fig. 6 shows a further modified form of my invention in plan, the button being shown in part section;

Fig. 7 a section on the line 7—7 of Fig. 6; 55
Fig. 8 shows a modified form of base plate in plan;

Fig. 9 the base plate of Fig. 8 with the button in place thereon and the pendant attached thereto;

Fig. 10 shows a still further modified form of base plate;

Fig. 11 the base plate of Fig. 10 with the button in place thereon;

Fig. 12 shows a plan view of a still further 65 modified form of my invention; and

Fig. 13 a section on the line 13—13 of Fig. 12.

Referring to the drawings in detail, and first of all to Figs. 1 to 4 inclusive, 1 designates a base plate of metal, as a metal stamping plate, for instance, this plate being provided with web-receiving openings or slots 2 and 3 with ears or lugs 4 and 5. The main portion of this plate may be of suitable shape 75 to conform to the shape of the base of a button to be attached thereto. In the present instance the base plate is substantially rectangular in plan. The bottom of the plate, that is to say, the space bounded by the ears 4 so and 5 and those portions of the plate in which are provided the slots 2 and 3, is provided with spurs 6 which are struck up out of the metal of the plate so as to project above the face thereof. Received by this metal base 85 plate and attached thereto as presently will be described, is a button 7. This button, as illustrated, is provided with an elongated head 8, a rectangular shank 9 and with a base 10. The base 10 is preferably in the form of two flanges, one at each side of the button shank, the upper face of each of these flanges being provided with a curved lip 11.

When the button 7 has been positioned on the base plate the ears 4 and 5 on the plate are bent over the base 10 of the button, as plainly indicated in Figs. 1 and 2, the ears engaging the lips 11. These ears or flanges 4 and 5 on the base plate, which might be termed holding lugs, are pressed into the rubber of the base of the button with some pressure sufficiently to at least deform the rubber of the base of the button as indicated in Fig. 2 so as to permit the rubber to extend above the top or beyond the ends of the holding lugs as indicated at 12 in Fig. 2. It will be seen that when the ears or lugs 4 and 5 are pressed down into holding position with

respect to the button, they will engage the lips 11 on the button base to thereby securely hold the button in place on the base plate. In addition to the foregoing, the spurs 6 on the base plate, when the ears 4 and 5 are pressed down into holding position, will be forced into the bottom of the base of the button to still further prevent any displacement of the button relatively to the base plate.

10 The non-elastic pendant designated 13 as a whole, has one lead 14 passing beneath the base plate over the end of the base plate, as indicated at 15, down through the slot 3 in the base plate and back beneath the base plate and button, and upwardly through the slot 2, over the end of the base plate, where the same may be stitched as indicated at 16, the stitching, of course, passing through both leads of the non-elastic.

20 The holding loop 17, which comprises two substantially straight parallel side arms 18, will, when slipped in place over the button head 8 as indicated in Fig. 2, be maintained out of contact at all times with the ears or lugs 4 and 5. Referring to Fig. 2, it will be seen that the ends of the base plate, which I will designate 19 and 20, are given a slight upward bend sufficiently to bring the lead, that is to say, the upper lead, of the non-elastic 30 above the level of the ears or lugs 4 and 5 so that when the loop 17 is moved or placed over the head of the button 8 it will rest upon this upper lead of the non-elastic to be thereby held out of engagement with the holding lugs. Furthermore, the rubber of the base of the button where it is squeezed out at the ends of the ears or lugs as indicated at 12 and as above pointed out, will also prevent the loop 17 from engaging the ears or lugs 4 and 5. Obviously, therefore, I have provided two means for preventing the holding loop from engaging the lugs 4 and 5, and either one or both of these means may be employed in actual practice, as desired.

45 From the foregoing it will be seen that I have provided a garment supporter structure employing a solid imperforate button held to a base plate by means which do not pierce the button, the holding loop being held out of engagement with these means at all times.

50 In Fig. 5 I have illustrated a construction which is very similar, in fact, almost identical with the construction above described, the button of this embodiment of my invention being 55 designated 7'. This button is held in place on a base plate by means of holding lugs, one of which is indicated and designated 5'. The button 7' is provided with a base similar to the base 10 of Fig. 3. The base plate 1', however, is not provided with web-receiving openings 2 and 3, one lead 14' of the non-elastic of the pendant passing beneath the base plate and button over the outer end of the base plate, as indicated at 15', and then down beneath the button, but across the upper face of

the base plate and up over the other end of the base where the two leads thus formed are stitched together as indicated at 16'. Consequently, when the ears or lugs 4 and 5 are pressed down into position, the pendant, that 70 is to say, one lead thereof, will be clamped between the button and base plate. In this figure also I have practically eliminated the upward bend designated 19 and 20 in Fig. 2 of the base plate and allowed the holding loop to 75 rest on the rubber of the button as indicated at 12', this rubber, as above explained, being pressed out or extruded by the ears on the base plate when these ears are pressed downwardly in attaching the button to the plate.

80 In this form of my invention, therefore, I have provided a garment supporter structure employing a solid rubber button and a base plate, the ears on the base plate holding the button thereto so as to eliminate the use of rivets and equivalent devices while the rubber of the base of the button is squeezed out or deformed sufficiently to maintain the holding loop 17' out of engagement with the holding lugs or ears on the base plate.

85 Figs. 6 and 7 illustrate a still further modified form of my invention. Referring now to these figures, 1² designates a base plate provided with web-receiving openings 2² and 3² and with holding lugs or ears 4² and 5². The button employed with this construction is designated 7² and comprises a base 10² adapted to be engaged by the holding lugs 4² and 5² above referred to. In this form of my invention, however, the base plate is of increased width as compared to the base plates so far described so as to provide a space 21 at each side of the shank of the button between the shank and edges of the bent-over ears 4² and 5², this space being of sufficient width to 100 permit of the reception of the side arms 18² by the holding loop. By this arrangement, therefore, it is unnecessary to have the ears 4² and 5² extrude the rubber of the base of the button, and it is unnecessary to bend the 105 ends of the base plate upwardly in order that the holding loop may be maintained out of engagement with the ears 4² and 5². In other words, this construction provides a garment supporter wherein the holding loop is maintained out of engagement with the holding lugs by which the button is attached to the base plate by providing a space for the reception of the side arms of the holding loop between the sides of the shank of the button 110 and the holding lugs.

115 In the embodiment of my invention shown in Figs. 8 and 9, I provide a structure in which I employ a solid button 7³. The base plate employed with this form of my invention is designated 1³ and comprises a metal plate which is depressed at 22 centrally of the base plate. The bottom of this depression is conveniently provided with spurs 6³ 120 corresponding to the spurs 6 in Fig. 4. At 125

opposite edges of depression 22 the metal of the base plate is provided with web-receiving openings 2³ and 3³ corresponding to the openings 2 and 3 of Fig. 4. The other two sides 5 of the depression 22, that is to say, the metal adjacent the sides of the depression is formed into holding lugs or ears 4³ and 5³, these ears, when bent over into button-attaching position, overlying the edges of the depression 10 22. The button 7³ in this form of the invention is placed in the depression 22 and the ears 4³ and 5³ bent over the base thereof to thereby securely hold the button against displacement in this depression. The spurs 6³ 15 aid in holding the button in position. The depth of the central depression 22 and the depth of the base on the button 7³ are of such proportions that when the ears 4³ and 5³ are bent over into button-holding position, the upper faces of the ears will not extend above 20 the plane of the upper face of the base plate. Referring to Fig. 9, the upper face of one of the ears or holding lugs is designated 23, and it will be seen that this part of the ear is 25 practically in the plane of the upper face 24 of the base plate,—at least it does not extend above this plane for a substantial distance. One lead of the non-elastic of the pendant which I will designate 14³ passes underneath 30 the button and base plate over the end of the base plate, as indicated at 15³, downwardly through the opening or slot 3³ of the base plate, beneath the button and base plate and upwardly through the slot 2³, where the 35 two leads of the pendant thus formed are stitched together as indicated at 16³. As a consequence of this construction, when the holding loop 17³ is moved into operative position with respect to the button 7³, the same 40 will rest upon the upper lead of the non-elastic of the pendant and be thereby maintained out of contact at all times with the ears or lugs 4³ and 5³ by reason of the fact that the upper faces of these lugs do not extend for 45 a substantial distance above the upper face 24 of the base plate.

Here, again, therefore, I have provided a garment supporter structure employing a solid button which, however, is securely attached to a base plate, the means by which the button is attached to the base plate being maintained out of contact with the holding loop at all times.

Referring now to Figs. 10 and 11, the base plate of these figures is designated 1⁴ and is provided with web-receiving slots 2⁴ and 3⁴. At the inner edges of each of these slots I provide a shoulder 25 which is struck up out of the metal of the plate and may be done when the slots 2⁴ and 3⁴ are being formed. The sides of the base plate are provided with ears or lugs 4⁴ and 5⁴ for attaching a button to the plate. These lugs are struck up out of the metal of the plate, as indicated at 26.

The button employed with this form of my invention is designated 7⁴ and is illustrated in Fig. 11. The base 10⁴ of this button is cut away as indicated at 27 so as to provide for the reception of the heads of the lugs 4⁴ and 5⁴ when the button is to be attached to the base plate. When the button is applied to the base plate and the ears 4⁴ and 5⁴ bent over into clamping position, it will be apparent that the rubber of the button will be pressed into the openings 26 in the base plate which are provided in the forming of the holding lugs or ears, and this will assist the ears in retaining the button on the plate. Then, again, the flanges or struck-up portions 25 at the edges of the slots 2⁴ and 3⁴ 80 will also prevent movement of the button on the plate, the base of the button, it being understood, fitting between these flanges, in other words, substantially filling the space between these flanges. This structure, therefore, provides a supporter in which the ears or lugs 4⁴ and 5⁴ will be out of contact with the holding loop (not shown) by reason of the fact that these ears will lie in the cut-out portions 27 in the button base. It will be apparent also that by this construction I have 85 eliminated the use of rivets and like devices, which permits of the employment of a solid button.

In Figs. 12 and 13 the base plate is designated 1⁵ and is provided, or may be provided, with web-receiving openings 2⁵ and 3⁵. This base plate is somewhat elongated as compared with the base plates above referred to and is provided with holding lugs 4⁵ and 5⁵, these lugs, however, instead of being at the sides of the button as in the cases above described, being at the front and rear faces of the button, in other words, adjacent the web-receiving openings 2⁵ and 3⁵. The button employed in this form of my invention is elongated, that is to say, has an elongated head 8⁵, the long axis of which, however, extends lengthwise of the base plate 1⁵ instead of crosswise or transversely as in the case of the structure above described in detail. The holding lugs 4⁵ and 5⁵ are of a length less than the distance between the side arms 18⁵ of the holding loop. In other words, these arms straddle the ears 4⁵ and 5⁵ and so far as these side arms are concerned will be maintained out of contact with the ears. In order that the cross bar 27 of the holding loop may not touch the forward ear or lug 4⁵ the button base is preferably provided with a depression 28 which is adapted to receive this lug so that the upper face of this ear or lug will lie below the under-side of the holding loop or the cross bar 27 of the holding loop.

In all of the forms of my invention above described, I have provided a hose supporter employing a solid button preferably of rub-

ber and cooperating with a holding loop of usual form, the button being securely attached to a base plate by means which are exterior of the button, that is to say, as distinguished from rivets and like devices which pass through the button, the holding loop, however, being maintained out of contact with this securing or attaching means at all times. It will be seen also that this result is obtained by causing the rubber underneath the ears or lugs by which the button is attached to its base plate to be extruded so that portions of the same will lie above the upper face of the holding lugs or by so shaping the ends of the base plate that the non-elastic of the pendant will be engaged by the loop so that the loop will be held above the holding lugs, or this result may be obtained by depressing the base plate, and so proportioning this depression and the base of the button that the ears when bent over to attach the button to the base plate will not extend sufficiently far above the base plate to be engaged by the holding loop. It will be seen also that any one or practically all of these constructions may be employed in the one supporter.

It is to be understood that the structures above described are illustrative rather than definitive and that therefore changes may be made therein within the purview of my invention.

What I claim is:

1. In a garment supporter structure, the combination of a button having a base, a base plate carrying the same, ears on the base plate intermediate the ends thereof adapted to be bent over the base of the button to attach the button to the base plate, the ends of the base plate beyond the ears being bent upwardly until the upper face of these bent-up portions lies substantially in the plane of the upper face of the ears.

2. In combination a base plate, a button carried thereby, a pendant for suspending the base plate, means forming a part of the base plate for attaching the button to the base plate, said base plate being bent upwardly at each side of the button attaching means and said pendant overlying a portion of said bent upward portion whereby the uppermost face of the overlying portion of the pendant is above the plane of the upper face of the button attaching means.

3. In a garment supporter structure, the combination of a button, a base plate, ears for attaching the button to the base plate, a pendant a portion of which overlies a portion of said base plate, and a holding loop cooperating with said button and engaging said

overlying portion of the pendant to be held thereby out of contact with said ears.

4. In a garment supporter structure, the combination of a button having a base, a base plate carrying the same, said base plate being provided with web-receiving openings or slots adjacent the ends thereof, ears on the base plate intermediate said slots and engaging the base of said button to attach the button to the base plate, a pendant for supporting said base plate and button, said pendant being threaded through said web-receiving openings or slots so as to overlie the ends of the base plate, and a holding loop cooperating with said button and adapted to engage said pendant to be maintained thereby out of contact with said ears.

5. As an article of manufacture, a button for garment supporter structures, said button comprising a head, a shank and a base integral with each other, the base of said button being provided with a lip at the outer upper edge thereof, said lip extending above the plane of the upper face of said base.

6. In a garment supporter structure, the combination of a base plate, spurs struck up from the metal of the main portion of said base plate, a button carried by said base plate, said button being provided with a base, lugs or ears on said base plate adapted to be bent over the base of the button to clamp the button to the base plate and to cause the said spurs to pierce the button base, portions of the material of the base of the button extending upwardly above the upper face of each of said lugs or ears, and a holding loop cooperating with said button and overlying said ears and maintained by the said upwardly extending portions of the button base out of contact with said ears.

7. A base plate for garment supporter structures, having ears or lugs intermediate the ends of the base plate adapted to be bent over toward the center of the plate to attach a button thereto, the ends of the plate beyond the said ears or lugs being bent upwardly so as to lie substantially in the plane of the upper face of each of said ears.

8. A base plate for garment supporter structures, comprising an integral metal plate, ears or lugs at each side thereof and intermediate the ends thereof, spurs struck up from the metal of the plate intermediate said lugs, the ends of said plate beyond the ears being bent upwardly to lie substantially in the plane of the upper face of said ears.

This specification signed this 26th day of June, 1926.

CARL J. HAZELTON.
